DIGITAL CLOCK

Seiji Toyoshima, 22-22, Nagaike-cho, Abeno-ku,
Osaka, Japan

Filed June 7, 1973, Ser. No. 367,783

Term of patent 14 years

Int. Cl. D10—01

U.S. Cl. D10—15

FIG. 1

FIG. 2

FIG. 3

FIG. 4

FIG. 5

FIG. 6

FIG. 1 is a front perspective view of a digital clock showing my new design with representative time indicia;

FIG. 2 is a top plan view thereof with the time indicating numerals not being shown for convenience;

FIG. 3 is a front elevational view thereof with the time indicating numerals not being shown for convenience;

FIG. 4 is a rear elevational view thereof;

FIG. 5 is a left side elevational view thereof, the right side being a mirror image thereto; and

FIG. 6 is a bottom plan view thereof.

I claim:

The ornamental design for a digital clock, as shown.
